(57) **CLAIM**

The ornamental design for a valve component for vehicle tyres, as shown and described.

DESCRIPTION

1.-4. Valve component for vehicle tyres

1.1 : Perspective

1.2 : Front

1.3 : Back

1.4 : Left

1.5 : Right

1.6 : Top

1.7 : Bottom

1.8 : Front view showing valve open state

The thin lines such as parallel lines and the like in the representation represent contours only and do not illustrate an ornamentation or decoration on the surface of the product.
